TENSIONING MEANS FOR LOOM WARP BEAMS

Ray M. Taylor, Quakertown, Pa.

Application August 29, 1951, Serial No. 244,154

4 Claims. (Cl. 139—100)

1

This invention comprises novel and useful improvements in a tensioning means for loom warp beams and more specifically relates to a friction brake tensioning mechanism for the warp beam of a loom.

The primary purpose of this invention is to provide a tensioning means for loom warp beams which shall maintain a constant tension upon the warp ends throughout the entire operation of the loom.

A further object of the invention is to provide a tensioning means in accordance with the preceding object which shall give a uniform pressure over substantially the entire surface of the warp beam.

Still another object of the invention is to provide a tensioning mechanism in accordance with the preceding objects wherein a friction brake applied to the head of a warp beam will be automatically released if greater than a predetermined tension is applied to the warp ends during operation of the loom.

A still further important object of the invention is to provide a tensioning mechanism which will maintain a uniform tension upon the warp threads regardless of whether the warp beam is substantially full or substantially empty of the warp threads.

The final important object of the invention to be specifically enumerated herein is to provide a self-adjusting tensioning mechanism for loom warp beams which shall be readily adjustable for different diameters of beam heads; and wherein the tension may be readily varied for different looms as required.

An important feature of the invention resides in the provision of a tensioning mechanism which will equally distribute the frictional pressure of a friction brake over the entire beam head surface. The mechanism in accordance with this invention attains this purpose by pulling in a reverse direction to the natural takeup motion as the weaving occurs. Because of the leverage action of the actuating mechanism of the friction brake assembly, a uniform friction brake pressure is applied over the entire circumferential area of the beam head.

A still further feature of the invention resides in the provision of mechanism wherein a uniform tension is maintained upon the warp ends during operation of the loom, and wherein this tension is released when the loom stops. Heretofore, the failure to relieve the tension upon the warp threads during stopping of the loom, results, upon restarting of the loom in the customary heavy

2

or "over beat" mark, commonly known in the art as "heavy starting marks." In the present invention, this disadvantage is overcome because the tension is increased in the warp ends as the loom starts, but is decreased in the warp ends when the loom stops because the friction between the friction brake and warp beam is released upon stopping of the loom.

The still further feature of the invention resides in arranging the friction brake band upon the loom beam end with the opening between the ends of the brake band preferably located at an angle of about 45° to a horizontal plane passing through the axis of the beam end.

Still another feature of the invention resides in the arrangement of a set of weights, one set of weights serving to maintain a uniform closing pressure upon the brake band to cause the same to frictionally engage the warp beam head of a loom, while the other weight serves to apply a constant force to the brake band for imparting a predetermined frictional drag to the warp beam head to thereby maintain a uniform tension on the warp beam ends thereon.

The foregoing, together with various ancillary features and objects of the invention are attained by the present invention, the preferred embodiment of which has been illustrated, by way of example only, in the accompanying drawings wherein:

Figure 1 is a rear elevational view of a warp beam of a loom showing the tensioning device in accordance with this invention applied thereto, parts being broken away and shown in section;

Figure 2 is a perspective view of a brake band assembly forming a part of the tensioning means of this invention, the same being shown disassociated from a warp beam head of a loom;

Figure 3 is a vertical transverse sectional detail view taken substantially upon the plane indicated by the section line 3—3 of Figure 1 and showing a normal position of the tensioning mechanism during operation of a loom;

Figure 4 is a view similar to Figure 3 but showing in somewhat of an exaggerated form the position of the mechanism as the latter releases its frictional grip upon the loom warp beam head;

Figure 5 is a fragmentary sectional view taken in vertical transverse section substantially upon the plane indicated by section line 5—5 of Figure 1;

Figure 6 is a vertical sectional detail view taken substantially upon the plane indicated by the section line 6—6 of Figure 5, and,

Figure 7 is a horizontal sectional view taken substantially upon the plane indicated by the section line 7—7 of Figure 2.

Referring now more specifically to the accompanying drawings, wherein like numerals designate similar parts throughout the various views, it is seen that the reference numeral 10 designates the warp beam of a loom which has an axle 12 and suitable supporting brackets 14 forming a part of the framework of a loom.

This warp beam is provided with the customary warp beam heads 16 and ropes or pulleys and a tensioning mechanism in accordance with this invention is applied to each of these heads in order to impart the predetermined tension to the warp threads 18, see Figures 3 and 4, which are secured to the warp beam. The purpose and functioning of a tensioning mechanism for warp beams is well-known to those skilled in the art, and a detailed explanation of the same is believed to be unnecessary. The improved tensioning mechanism in accordance with this invention consists of an arcuate friction brake, which as shown in the drawings includes an inner friction brake lining 20 of any suitable material which as shown in Figure 7 is attached to a steel outer band 22 as by rivets 24. A strap 26 of any suitable material is disposed about the exterior surface of the steel band 22, one end of this strap being secured to an end of the inner band 20 and the steel band 22 as by a fastening bracket 28 attached thereto by suitable rivets 30. The inner and outer members 20 and 22, at their other ends have secured thereto a second bracket 32 by rivets or fasteners 30.

The friction band assembly previously described is adapted to encircle the warp beam end 16 and frictionally embrace the same for applying a frictional drag thereto. Obviously by regulating the extent of this frictional drag or braking action any desired tension may be maintained upon the warp threads 18 as the latter are let out from the warp beam during operation of the loom.

The brake actuating means, as shown best in Figures 2, 5 and 6, consists of an actuating lever 34 having a bifurcated extremity 36 which is pivotally attached to the bracket 32 as by a rivet or pivot pin 38, the end 36 being received between upstanding lugs 40 upon the bracket 32.

At its outer end, the actuating lever 34 is provided with a plurality of notches 42 for a purpose which will be later set forth.

An adjustable connecting link in the form of a rod 44 has one end fastened as by a pivot pin 46 between the pair of lugs 48 carried by the bracket 28, and its other externally threaded end 50 is screw-threadedly engaged in a diametrical bore in a retaining pin 52. The rod 44 is received between the bifurcated end portions of end 36 of the lever, and the pin 52 is journaled in the furcations as will be readily apparent from Figures 5 and 6.

By virtue of the arrangement shown in Figures 2 and 5, it will be apparent that moving the lever 34 downwardly about its pivot pin 38 will serve to pull the two adjacent ends of the friction brake bands closer together thereby causing the brake bands to more tightly embrace and increase their frictional drag upon the beam head 16. Reverse movement of the lever will of course tend to expand the bands and decrease the frictional braking effect upon the heads.

As will be apparent from Figure 1, the identical

tensioning friction brake assembly is applied to each end of the warp beam to the heads 16 thereof.

The warp tensioning weight indicated generally by the numeral 54 is operatively connected to the member 26 for applying the tensioning force, to the friction brake assembly to the warp beam heads 16 to thereby tension the warp threads 18. For that purpose, there is provided a fulcrum or supporting bracket 56 having a lever 58 pivoted thereto as by a pivot pin 60. This lever at its extremity is provided with a plurality of notches 62, upon which the weight 54 may be selectively engaged by the hook member 64. Intermediate the ends of the lever 58, the free end of the member 26 is folded in the form of a loop 66. A clamp consisting of a pair of plates 68 and 70, secured together by bolts 72 is provided for maintaining the end of the member 26 in tight engagement upon the lever 58. If desired, one or both of the plates 68 may be serrated or notched as at 74 in Figure 2.

In normal operation, the length of the member 26 is such that the weights 54 will be above the floor or the supporting surface and thereby impart a uniform force to the end of the member 26 and thereby a uniform frictional drag to the brake assembly to the warp beam ends 16.

The brake weight member indicated generally by the numeral 76 is secured by any desired clamping device 78 to a loop 80 at the lower end of the cable 82 whose upper end is provided with a loop 84, retained as by a clamping device 86, this upper loop being selectively placed in one of the notches 42 of the lever 34.

It will be particularly noted that the warp tensioning cable or member 26 is disposed on the opposite side of the warp beam axle 12 of the brake tensioning cable 82.

The operation of the device is as follows:

The running off of the warp threads 18 from the warp beam during operation of the loom causes the clockwise rotation of the warp beam as viewed in Figures 3 and 4. The brake weight 76 which normally rests upon the floor applies a force movement to the actuating lever 34 to the friction brake assembly which movement is in the same direction of rotation as that applied by the warp threads 18 as the latter are let off of the warp beam. Since the weight 54 is normally off of the floor, the member 26 is under a tension corresponding to the weight 54, the tension of the member 26 tending to rotate the assembly in a counterclockwise direction.

The tension weight 54 thus produces a force moment which is of the opposite direction to the moment produced by the warp threads 18 upon the warp beam. The moment of the tension weight is thus oppositely directed to that of the brake actuating weight.

The brake actuating weight 76 thus imparts a constant bias acting through the brake member 34 which tends to contract the brake band with a constant force and thereby tends to maintain a constant friction or drag of the brake assembly upon the warp beam head. Through this drag the weight 54 tends to oppose rotation of the warp beam and thereby maintains a tension upon the warp threads which is constant and which corresponds to the weight 54. However, if the brake assembly is too tightly clamped upon the warp beam head, and tends to rotate with the latter, this rotation will move the actuating lever 34 in a clockwise direction, this movement being shown in exaggerated

fashion in Figure 4. In response to this movement, the tension of the cable 82 is relieved whereby the brake band assembly is expanded, and the pull on the end of the member 26 attached to the bracket 28 further serves to hold the brake band assembly at its upper end as shown in Figure 4. This motion lifts the frictional drag of the assembly and thereby lessens the tension upon the warp threads.

By the foregoing a constant self-adjusting tension is maintained upon the warp beam ends and thereby upon the warp threads.

By comparing Figures 3 and 4 it will be seen that with the loom in normal operation the pivot pin 38 of the bracket 32 lies upon the radius 90 which is inclined with respect to the vertical radius 88 by an angle indicated at 92. However, when the tension upon the warp threads become too great, or exceeds that for which the device has been set, the brake band assembly tends to rotate with the warp beam head, this pivot pin moves to a radius indicated at 96 and which defines an angle 94 with the radius 88, this angle being obviously less than the angle 92.

It will be further observed that by means of the adjustable connecting rod 44 joining the two ends of the brake band assembly, that a uniform circumferentially and peripherally extending tension can be applied throughout the entire brake band to cause the same to uniformly frictionally grip the surface of the drum.

In this device, when the operation of the loom ceases, there is no altering in the clockwise moment applied to the beam head by the letting off of the warp ends therefrom, and consequently the weight 54 of the member 26 is now free to cause the counterclockwise moment of the end of the brake band assembly to which the bracket 28 is attached, this moment tending to move the parts from the position shown in Figure 3 to a position somewhat similar to that in Figure 4. During this moment, an upward thrust is imparted to the rod 44 which tends to lift the bracket 32 and the connecting rod 44 therewith, this resulting in a relative clockwise rotation of the lever 34 about the pivot 38 to thereby loosen the brake bands assembly and release or at least reduce the tension upon the warp end threads thereon. Thus, when the loom is idle, the tension upon the warp threads is reduced to that upon starting of the loom tension is again increased.

From the foregoing, the construction and operation of the device will be readily understood

and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

Having described the invention what is claimed 10 as new is:

1. A tensioning device for a loom warp beam comprising a friction brake band adapted to embrace a loom warp beam head with its ends in spaced relation, brake actuating means engaging 15 said brake band ends for varying the frictional gripping force of said band upon a beam head, a warp tension weight, means connecting said warp tension weight to said brake band for exerting pull opposite to that of the warp 20 threads, a brake weight, means connecting the latter to the brake actuating means for applying force to said brake actuating means.

2. The combination of claim 1 wherein said weights are on opposite sides of the axis of the 25 warp beam.

3. The combination of claim 1 wherein said brake actuating means includes an operating lever having one end pivoted to one brake band end, means connecting the other end of said 30 brake band to said operating lever adjacent said one end thereof, said brake weight connecting means being secured to said operating lever adjacent its other end.

4. The combination of claim 1 wherein the 35 means connecting the warp tension weight comprises a lever fulcrumed at one end, said warp tension weight being adjustably secured to the other end of said lever, a member connecting said lever to said brake band.

40 RAY M. TAYLOR.
